SHELL INSPECTION APPARATUS

Adolph F. Dauber, Elam, Pa., Antoine F. Gagne, Jr., Stratford, Conn., and Charles R. Johnson, Glenn Mills, Pa., assignors to E. I. du Pont de Nemours & Company, Wilmington, Del., a corporation of Delaware

Application June 1, 1951, Serial No. 229,374

2 Claims. (Cl. 209—72)

1

The present invention relates to an apparatus for the sorting and inspection of blasting cap shells. More particularly, this invention provides an assembly adapted to sort and remove blasting cap shells, which are not up to standard, efficiently and rapidly, and with a minimum amount of human supervision.

Blasting caps are assembled by the millions annually for commercial users of explosives. Because of their basic function of initiating the main charge, blasting caps must be of high quality and of uniform standard. The blasting cap shell, or container for the explosive charge and initiating means, is an important element in determining the performance and utility of blasting caps since it is the shell which possesses the rigidity and strength necessary to maintain the various units of a blasting cap in the proper relationship despite rough handling, and which protects the units from contact with moisture and other deleterious substances.

The blasting cap shells most predominantly used by the industry are metallic, although recently attention has been given to the use of various plastics. The metallic caps are generally fabricated by cold-drawing copper or aluminum to form tubular containers having one end thereof closed.

In the manufacture of blasting cap shells by the above procedure, or by substantially any alternative procedure, it is inevitable that a certain percentage of the shells thus produced will contain defects which render them unsuitable for use. These defects may be extremely difficult to detect, particularly by visual means. The imperfections may consist of such things as slight perforations in the walls or end closure, unevenness of the open ends, splits in the walls, weakened side walls, etc. In addition to the above named imperfections, a frequent cause of difficulty is found in shells of uneven length. In some processes shells are loaded and assembled mechanically, and a lack of uniformity in length may produce blasting caps which will not fire. If the shell is too short, the bridge wire may be broken by contact with the pressed charge of explosive, or the closure plug may not be sufficiently anchored to prevent later movement. On the other hand, if the shell is too long, the bridge wire may be too far from the explosive charge to ignite it, or the loading mechanism may become jammed.

In the past, shell inspection has been performed by a battery of skilled workers who had to check each shell individually. It is natural that in handling a large number of shells, most of which are satisfactory, an appreciable number

2

of slightly defective shells will pass this inspection and later cause difficulty. Due to the small sizes of the various cap shells, this manual handling and inspection is extremely fatiguing and bothersome, as well as costly.

It is, therefore, an object of the present invention to provide an apparatus which will eliminate the need of individual handling of blasting cap shells. It is a further object of the present invention to provide an apparatus which will efficiently and rapidly reject imperfect blasting cap shells. An additional object of the present invention is to provide an apparatus for the inspection and sorting of blasting cap shells which requires a minimum amount of human supervision. Additional objects will become apparent as the invention is further described.

We have found that the foregoing objects may be achieved by providing, in combination, a means for separating and aligning individual shells from a jumbled mass of shells; a means for subjecting each shell to a mechanical test for perforations, splits, unevenness, etc., a means of rejecting defective shells and passing satisfactory shells, a means for determining which shells are of non-uniform length and of removing them, and a means of presenting the shells for a final visual inspection in such manner that any previously undetected flaws are attention directing.

An apparatus which is adapted to provide the necessary means is fully illustrated in the accompanying drawings, and the present invention may be more completely described by reference to the various drawings. It is to be understood that many of the elements making up the complete assembly are capable of replacement with alternative elements differing in operation but not in function. The drawings, therefore, are intended as illustrative, and not as limiting the present invention.

In the drawings,
Figure 1 represents a frontal view of an assembled inspection apparatus; and

Figure 2 represents a top view of the same assembly.

Figure 3 represents a frontal view of the separating and aligning unit of the assembly; and

Figure 4 represents a detailed view of a section of the separating and aligning unit of the assembly; while

Figure 5 represents a side section of the separating and aligning unit, and a detail of an inspection element;

Figure 6 represents an embodiment of a height inspection unit used in the present assembly, and also shows the differential belt used to rotate the shells slowly as they pass before the operator.

Using the line F-F as the floor level, 1 is a supporting framework of steel for the working parts of the apparatus, 2 is a floor level receiving bin for uninspected shells, 3 is the sorting assembly which also partially inspects the shells, 4 is a reject bin, 5 is the visual inspection assembly, and 6 is the container for the satisfactory, inspected shells.

As shown in Figures 1 and 2, the shells are conveyed from the receiving bin 2 to the sorting assembly 3 by means of an endless conveyor chain 7 which travels within the housing 8. After the shells pass through the sorting assembly 3, they are carried to the visual inspection assembly 5 by means of an endless chain 9 containing evenly spaced pins 10. The endless chain 9 moves continuously and is guided by means of sprocket wheels 11 and drive sprocket 12 which projects from the sorting assembly 3. The sorting assembly 3, the conveyor chain 7, and the endless chain 9 are driven by means of an electric motor 13 and gear reducer (not shown) through the chain 14. After the shells pass the inspection assembly 5, they drop into the receiving funnel 16, from which they pass to the container 6.

The sorting assembly 3 illustrated in Figures 3, 4 and 5 consists primarily of a drum 16 containing a number of helical grooves 17, a face plate 18 containing slanted openings 19 to permit the passage of the shells from the drum 16 to matching labyrinth sections where the shells are aligned and partially tested. The labyrinth sections all have a cover plate 21 which is secured with quick-opening screw fasteners 22 for speedy jam clearance. The sorting drum 16 and the face plate 18 containing the labyrinth sections 20 are supported by means of an axle shaft 23 which is in turn supported by means of front bearings 24 and rear bearings (not shown) located in an inwardly projecting hollow sleeve of the sorting assembly housing 25, the housing 25 being fastened to the support frame 1. The axle 23 contains passageway 26 leading from an outside vacuum connection 27 to multiple vacuum test units 28. Each vacuum test unit 28 consists of passageway 29 leading to a spring loaded poppet valve 30 which is actuated by means of cam actuated tappet 31 governed by the groove 32 in the fixed cam ring 33. 34 is a chamber between poppet valve 30 and poppet valve 35, the latter being actuated by means of tappet 36, cam groove 37 and fixed cam ring 38. Passageway 39 leads to the outside of the assembly (open air), and passageway 40 leads to a resilient sealing disc 41. Drive sprocket 12 is connected to a projecting end of the axle shaft 23.

The labyrinth sections 20 consist of machined pieces 42 to 50 so arranged as to form passageways for the shell to travel, a movable escapement jaw 51 connected by shaft 52 through spring 68 to cam roller 53 operating in cam groove 54 of cam ring 55, and a shell alignment pin 56 projecting from piece 42. The labyrinth cover plate 21 contains shell guiding nozzle 57 to direct the shell from the labyrinth section 20 to the carrying pin 10 of the chain 9.

The visual inspection assembly 5 includes electric micro-switches 58, 59 and 60, and their respective contact arms 61, 62 and 63; shell rotating belt 64, and inspection table 65. At the portion of the assembly under arm 62 of microswitch 59 is the shell ramp 66.

In operation, the shells are manually or mechanically dumped into the receiving bin 2 after they have been fabricated and washed to re-

move loose particles. By means of the conveyor chain 7, which contains a plurality of bucket shaped scoops, shells are continuously lifted from the bin 2 and dropped into the sorting drum 16 through the opening 67 of the sorting assembly housing 25. The rotation of the drum 16 tumbles the shells at the bottom, and fills the helical grooves 17. The grooves are so machined that shells which are not horizontal with respect to the grooves 17 are not retained thereby, but will be knocked out by other shells in the drum.

As the drum 16 rotates in a clockwise direction, the contour of the helical grooves 17 causes the shells lying in them to slide toward the face plate 18 and into the openings 19. As each labyrinth section 20 reaches approximately a ten o'clock position, the shell slides through the opening 19 into the escapement jaw 51.

When the labyrinth section reaches approximately the one o'clock position, the inward curve of the cam groove 54 of cam ring 55 causes the cam roller 53 to depress the shaft 52 inwardly, thereby moving the escapement jaw 51 toward the piece 45. In the event that the shell is too long, or has not fully cleared the opening 19, damage or jamming of the jaw is prevented by the spring 68 which permits the cam roller 53 to move, without moving shaft 52. The late timing and the angle between 51 and 19 serve to help separate the shell in 51 from the one following in 19. A shell which has fully entered the jaw 51 slides to the orientation pin 56 of piece 42. The distance between the piece 43 and the base of the pin 56 is slightly larger than the length of the shell, while the distance between the piece 43 and the point of the pin 56 is less than the length of the shell. If the shell slides with the open end towards piece 42, it will rest on piece 42, but if it slides with the closed end towards piece 42, it will rest on the pin 56. As the labyrinth section 20 approaches the four o'clock position, gravity causes the shell to drop towards the outer portion of the space between pieces 42 and 43. If the open end is toward piece 42, the closed end moves first swinging around the arc of 43, while if the closed end is toward the pin 56 the top is trapped by 43 and the closed end slides off the pin into the pocket in 42. In either event, the shell ends up with the open end facing toward the center of the sorting assembly 3. At about the ten o'clock position, this shell slides around the outside of 43, between 46 and 49, and then 47 and 50 to the resilient disc 41. At this same position, a second shell enters the jaw 51 to begin the same route.

At about the twelve o'clock position, poppet valve 35 is closed by the rearward movement of tappet 36, and poppet valve 30 is opened by forward movement of tappet 31. The air in the shell and in the passageway 40 and the chamber 34 is thereby exhausted through the shaft passageway 26. By about the two o'clock position, poppet valve 30 is spring closed following the rearward movement of tappet 31. If the shell is sound, and the lips of the open end even, the vacuum in the shell is maintained and atmospheric pressure keeps the shell tightly pressed against the resilient disc 41 as the unit continues to rotate. If the shell is not sound, or if the lips are uneven or torn, the vacuum is lost and the shell drops through the passageway between pieces 46 and 47, and so on out past piece 42 to the reject bin 4.

At about the seven o'clock position, poppet

valve 35 is opened by forward movement of tappet 36, thus permitting air to enter the shell and chamber 34 through the passageway 39. The movement of the tappets is governed by the curvature of the grooves 32 and 37 in the cam rings 33 and 38 respectively. At this position, piece 49 has pivoted by gravity to close the passageway between it and piece 46, so that the released shell drops into the space between piece 49 and piece 45. At about the ten o'clock position, this shell slides down the passageway between pieces 45 and 50, through the shell guiding nozzle 57 onto a pin 10 of the chain 9. Simultaneously, a third shell is entering the movable jaw 51.

The shells are carried on the pins 10 under the arm 61 of microswitch 58. The pins 10 are slightly longer than the shell, and the microswitch 58 is set to break contact if the arm 10 is raised more than the normal height of the pin and the bottom thickness of the shell. Such increased height could be caused by the interior of the shell being partially blocked, for instance by a broken punch, or by the lips being slightly compressed so that the shell does not rest properly on the tapered pin. The breaking of contact will stop the machine, thereby permitting the operator to remove the defective shell.

The shells are then carried across the rear of the visual inspection table 65 and are contacted by the slowly-moving shell-rotating belt 64, which imparts a slow rotation to the shell on the pin. Due to this rotation, the operator, by visual inspection, can easily observe any defects such as pitted walls. After passing this point, the shells arrive at the shell ramp 66, which lifts the shells partially off the pins. The shells now pass under the contact arm 62 of microswitch 59. If the shell is shorter than standard the current to the motor is interrupted, permitting the operator to remove the irregular shell. In order to eliminate stoppage of the assembly in the case of an empty pin, the contact arm 63 of microswitch 60 is positioned horizontally so that when an empty pin permits movement of arm 63, microswitch 60 closes a by-pass circuit to the motor.

The fully inspected shells are retained on the pins 10 by the shell guide 69 as the pin chain 9 engages the sprocket wheel 11 at the end of the inspection assembly and changes direction. The ending of the shell guide 69 permits the shells to drop off of the pins 10 into the receiving funnel 10 and the container 6.

In the foregoing description, any clock positions mentioned refer to the center line of the labyrinth sections 20, and are merely approximations since, within limits, the action points may be varied several degrees in either direction. In the drawings, an assembly having twelve labyrinth sections has been illustrated. The number of sections is limited only by the size of the hopper and the size of the shell, and it is apparent that the number of sections will 65 determine the number of shells inspected during each revolution of the drum.

In view of the fact that the movement of the shells through the labyrinth is entirely due to the force of gravity, the speed of rotation and 70 hopper diameter must be below that at which the centrifugal forces would interfere with the force of gravity. It can thus be seen that for maximum production, a plurality of labyrinth sections is preferable, even though the appara-

tus must thus be made larger and more expensive. The great advantage in utilizing a labyrinth sorting assembly operative by gravity alone is that the need for mechanical gripping of the shells is eliminated, thereby reducing the likelihood of damage to the shells during the sorting and testing. The assembly is also simpler and cheaper than an equivalent continuous-motion mechanical grip machine.

10 While the invention has been completely described with reference to the apparatus illustrated by the accompanying drawings, it is apparent that many variations in the sequence of operational steps, construction and design of 15 the structural elements, and the inclusion of additional stages can be made without departing from the scope of the invention. Accordingly, we intend to be limited only by the following claims.

We claim:

1. A shell sorting and testing device comprising in combination a rotatable drum, at least one helical groove on the inner periphery of said drum, a back-plate at one end of said drum, 25 said back-plate being open in the central portion for admittance of blasting cap shells, a face plate at the opposite end of said drum, said face plate having an opening in alignment with said helical groove, a supporting axle centrally-disposed within said drum and projecting beyond said face plate and said back-plate, a motor in engagement with said axle, a stationary housing about said drum, a cam ring attached to said housing, a cam-operated jaw at the openings of 30 said face plate, at least one labyrinth arrangement on said plate, a cover containing a nozzle over said labyrinth arrangement, at least one vacuum test disc mounted on said axle directly in front of said face plate, a channel in said 35 disc communicating with a valving means for controlling evacuation of air from said channel, a passage within said axle connecting said valving means with a vacuum pump, a passageway in said labyrinth arrangement adapted to 40 guide a shell from said jaw to said vacuum test disc, a passageway in said labyrinth arrangement adapted to guide a shell from said disc outside the periphery of said face plate, and a passageway in said labyrinth arrangement 45 adapted to guide said shell from said disc to said nozzle in said cover, the motion of the said shell being influenced by the force of gravity during rotation of said drum.

2. A shell sorting and testing device as claimed 50 in claim 1, wherein the drum contains a plurality of helical grooves, and an equal number of labyrinth arrangements and vacuum test discs are present.
